UNITED STATES PATENT OFFICE.

WALTER SCHULTZ, OF NEW YORK, N. Y.

HEATING STOVE.

Original application filed March 26, 1923, Serial No. 627,776. Divided and this application filed June 20, 1923. Serial No. 646,562.

To all whom it may concern:

Be it known that I, WALTER SCHULTZ, a citizen of the United States, and resident of the city of New York, in the county of Bronx and State of New York, have invented certain new and useful Improvements in Heating Stoves, of which the following is a specification, the same being a division of application for United States Letters Patent Ser. No. 627,776, filed March 26, 1923.

The present invention relates to improvements in electric stoves, and more particularly to that type which has the structure or form of a radiator.

15 The main object of the invention is to provide a stove of the character mentioned, wherein the heat radiating walls are formed of sheet metal, and means are provided for heating and circulating a current 20 of air.

A further object of the invention is to provide a stove of the type mentioned having heat radiating walls which are given a rotary motion, thereby effectively giving off 25 the heat to the surrounding air.

A further object of the invention is to produce a heating stove which is simple in construction, efficient in operation, durable in use and capable of manufacture on a 30 commercial scale, or in other words one which is not so difficult to make as to be beyond the reasonable cost of such a contrivance.

With these and other objects in view, 35 which will more fully appear as the nature of the invention is better understood, the same consists in the combination, arrangement and construction of parts hereinafter described, pointed out in the appended 40 claim and illustrated in the accompanying drawings, it being understood that many changes may be made in the size and proportion of the several parts and details of construction within the scope of the 45 appended claim, without departing from the spirit or sacrificing any of the advantages of the invention.

A few of the many possible embodiments of the invention are illustrated in the accompanying drawings, in which:—

Figure 1 is a front elevation, partly in section, of a stove constructed in accordance with the present invention; Fig. 2 is a similar elevation of a modified construction; 55 Fig. 3 is a similar elevation of a further

modification of the invention; Fig. 4 is a top plan view of the stove shown in Fig. 3; Fig. 5 is a central vertical section taken through a further modification of the invention; and Fig. 6 is a top plan view of the 60 stove shown in Fig. 5.

Referring now first to the heater illustrated in Fig. 1 of the drawings, the numeral 10 indicates an elongated horizontally extending heating chamber, mounted upon 65 legs 11. With this chamber communicate tubular radiating bodies 12, extending, preferably, vertically and being made of sheet metal. The heating chamber is also made of sheet metal, although this is not essential. In the bottom of the heating chamber are formed air inlets 13, the radiating bodies being provided adjacent their tops with air outlets 14, which are controlled by a gate or slide 15. Within the heating chamber is 70 disposed an insulating body 16, preferably in the form of a bar, on which are wound resistance coils 17 in an electric circuit, that is supplied with energy from any suitable source. A switch or similar means may be 75 employed for controlling the flow of electric energy into the resistance coil. For this purpose a plug 18 of any preferred construction is used in the stove shown in Fig. 1.

The heat generated serves first to heat 80 columns of air which flow from the air inlets 13 into the heating chamber and leave the radiating bodies through the outlets 14. In addition to this, the radiating bodies are 85 also heated, giving off the heat by direct 90 radiation. As the sizes of the outlets 14 are varied by means of the gate or slide 15, the quantity of air passing through the heater is changed according to the requirements. 95

The modification illustrated in Fig. 2 of the drawings comprises a heating chamber 19, with which communicates a radiating coil 20, both the coil and chamber being made of sheet metal. The chamber is provided with air inlets 21 and the free end of the coil with air outlets 22. The air inlets and also the air outlets are controlled by a valve 23. Within the heating chamber is disposed an electric heater 24 of the type 100 described in connection with Fig. 1 of the drawings. The operation of this device is obvious from the foregoing.

The modification illustrated in Figs. 3 and 4 of the drawings comprises a hollow 110

radiating body 25, extending, preferably, vertically and having a star-like transverse cross-section. This body is made of sheet metal, is open at its bottom and closed at its top. The radiating body is mounted upon legs 26, whereby free access of air to the radiating body is provided, the heated air leaving the radiating body through outlet openings 27 in its top, which outlets are controlled by a valve 28 of any suitable construction. An electric heater 29 is disposed in the radiating body, above its open bottom, heating the current of air circulating through the radiating body and also heating the said body, which gives off heat by direct radiation.

The modification illustrated in Figs. 5 and 6 of the drawings comprises a hollow base 30, on which is mounted a heating chamber 31, carrying a vertically extending spindle 32. On this spindle is mounted a radiating body 33 of the type described in connection with Figs. 3 and 4 of the drawings, the only difference being that it is closed at its bottom, as shown at 34. Both this bottom and the top of the radiating body may be provided with perforations 35, those in the bottom forming air inlets and

those in the top air outlets. Within the heating chamber is disposed an electric heater 36. The radiating body is, when the heater is in operation, continuously rotated, for instance by means of an electric motor 37, by the intermediary of a train of gears, including in the case illustrated a gear 38 on the shaft of the motor, and in mesh with a gear 39, which is fixed to a vertically extending spindle 40, the said spindle carrying also a pinion 41, in mesh with an internal gear 42, which is secured to the underface of a bottom 34 of the radiating body. When the circuit of the motor is closed, the radiating body 33 is rotated on the spindle 32, thereby giving up heat to the surrounding air.

What I claim is:—

An electric heating stove, including a radiating body through which air is adapted to circulate, an electric heating body for heating the air flowing through said radiating body, and means for rotating said radiating body.

Signed at New York, in the county of New York, and State of New York, this 31st day of May, A. D. 1923.

WALTER SCHULTZ.
